UNITED STATES PATENT OFFICE.

GEORGE D. GRIZZARD, OF NORTH EMPORIA, VIRGINIA.

PEANUT DIGGER.

Application filed September 7, 1926. Serial No. 133,983.

The present invention relates to a peanut digger, and has for its prime object to provide a structure wherein a pair of wheeled frames are connected and have means associated therewith so that the rear frame may be adjusted in relation to the front frame for controlling the depth of the digging element mounted on said rear frame.

Another very important object of the invention lies in the provision of a device of this nature which is exceedingly efficient and reliable in digging peanuts and which will leave the soil in excellent condition for clover, grain, or the like.

A still very important object of the invention lies in the provision of a peanut digger of this nature which is exceedingly simple in its construction, inexpensive to manufacture, easy to manipulate in its adjustment, strong and durable, and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

30 In the drawing:—

Figure 1 is a side elevation of the peanut digger embodying the features of my invention, showing a portion in section,

Fig. 2 is a top plan view thereof,

35 Fig. 3 is a detail vertical section taken substantially on the line 3—3 of Fig. 2, and

Fig. 4 is a detail perspective view of the digging elements.

Referring to the drawing in detail, it will be seen that the numeral A denotes the front frame and the numeral B the rear frame. The front frame A includes a substantially horizontally disposed plate 5 mounted on an inverted U-shaped axle structure 6 on which are journaled wheels 7. A draft tree 8 is engaged on the front end of the plate 5 by means of a bracket 9. Braces 10 extend from the front end of the plate to the extremities of the axle structure 6. An arcuate slot 11 is formed in the rear of the plate 5 and extends transversely thereof. The rear end of the bracket 9 terminates in a loop 12 which is engaged in an eye 14 formed in the forward end of a plate 15 slidable on the rear portion of the plate 5.

55 A bolt 16 extends from the plate 15

through the slot 11. The slot 11 is concentric in relation to the loop 12 so that the plate 15 may swing in an arc on the plate 5. A riser 17 is preferably cast integrally with the plate 15 and has a vertical rear portion designated specifically by the numeral 18 and provided with a vertical series of openings 19. A lever 20 is pivotally engaged with one of the openings 19 by means of a pin 21. A pair of curved rods 22 is engaged as at 25 intermediate their ends with a toothed segment 24. There is one of these rods 22 on each side of the segment 24 and they extend rearwardly and outwardly, and downwardly, as is clear from an inspection of Figs. 1 and 2. The forward ends of the rods 22 straddle the riser 17.

Another object of the invention is the provision of a device for engaging the toothed segment 24. Auxiliary rods 27 are engaged between the rods 22 and with the toothed segment 24 at 25 and extend downwardly and further rearwardly than the rods 20.

The rear frame B includes a pair of parallel spaced beams 28 from which rise sides 29. The forward ends of the sides 29 and the beams 28 are engaged with the lower ends of the rods 22 and 27 as is indicated at 30. A bracket structure 31 includes a plurality of legs having their extremities attached to the beams 28 and on the upper portion of the bracket structure there is disposed a seat 32.

An axle 33 is fixed as at 34 to the beams 28 to extend transversely under the rear portions thereof and under the seat 32. The beams 28 normally incline downwardly and forwardly in respect to the axle 33. A digging element is denoted generally by the letter D and is in the form of a blade having its longitudinal edges converging from intermediate points forwardly to a point 35. The rear portion of the blade is bent longitudinally and provided with longitudinally extending slots 36 forming scattering tines 37. The blade is further provided with a pair of openings 38 one adjacent each side edge intermediate the ends thereof for being pierced by bolts 39 which pierce suitable openings in the forward ends of the beams 28.

As the implement is being pulled forwardly, it will be seen that by proper manipulation of the lever 20, the digging element may be adjusted in respect to the ground as may be desired so that the peanuts may be

dug therefrom and the peanuts and soil will be moved upwardly on the blade and somewhat scattered by the tines 37, so that the peanuts may be easily gathered from the broken up soil. The machine will leave the soil in an excellent condition for grain, clover, and the like.

With this machine, it is only necessary to go over the row once, because the digging element may always be maintained at the proper depth.

It is thought that the construction, operation, and advantages of this invention will now be clearly understood by those skilled in this art without a more detailed description thereof. The present embodiment of this invention has been disclosed in detail merely by way of example, since in actual practice it attains the features of advantage enumerated as desirable in the statement of the invention and the above description. It will be apparent that numerous changes in the details of construction, and in the combination and arrangement of parts may be resorted to without departing from the spirit

or scope of the invention as hereinafter claimed, or sacrificing any of its advantages.

Having thus described my invention, what I claim as new is:—

An agricultural digging device of the class described including in combination, a front wheeled frame, a casting on said frame, a lever pivoted to said casting, a toothed segment pivotally engaged with said lever at an intermediate portion thereof, a detent on said lever engageable with said segment, rods having intermediate portions fixed to the segment, their forward ends straddling the casting, their rear ends extending downwardly and outwardly, a rear wheeled frame including a pair of parallel spaced members attached at their forward ends to said rods, an axle extending across the rear portion of said means, and having wheels journaled thereon, a blade fixed to the forward portions of the means.

In testimony whereof I affix my signature.

GEORGE D. GRIZZARD.
